UNITED STATES PATENT OFFICE.

FRANKLIN L. BAKER, OF CHICAGO, ILLINOIS, ASSIGNOR TO STANDARD CAR TRUCK COMPANY, OF CHICAGO, ILLINOIS, A CORPORATION OF NEW JERSEY

ROLLER SIDE BEARING.

1,425,741.

Specification of Letters Patent. Patented Aug. 15, 1922.

Application filed November 22, 1920. Serial No. 425,681.

To all whom it may concern:

Be it known that I, FRANKLIN L. BAKER, a citizen of the United States, residing at Chicago, in the County of Cook and State of Illinois, have invented certain new and useful Improvements in Roller Side Bearings; and I do hereby declare the following to be a full, clear, and exact description of the invention, such as will enable others skilled in the art to which it appertains to make and use the same.

This invention relates to a roller bearing, and particularly to a side bearing for railway cars, which bearing is adapted to be supported upon and carried by the truck bolster, and the rollers thereof adapted to bear upon the wearing surface provided on the body bolster of the car.

It is an object of this invention to provide such a bearing having a plurality of bearing rollers and automatically operated mechanism tending to maintain said bearing rollers in their central and normal position and to assist them in returning to this position when moved therefrom.

This, and other objects and advantages of the invention will become apparent as the description proceeds in connection with the accompanying drawings, in which like reference characters refer to the same parts throughout the different views, and in which

Fig. 1 is a view of the device in side elevation;

Fig. 2 is a partial top plan view;

Fig. 3 is a view of the device in end elevation, a part thereof being in section; and

Fig. 4 is a view in side elevation showing the bearing at one extreme position of the travel of the roller.

Referring to the drawings, the bearing is seen to comprise a frame member of general rectangular form and which has a horizontal base plate 1, around the outer sides of which depends the surrounding flange 2, which, together with the cross ribs 3 and bolt lugs 4 form the lower surface of the frame member. The base member 1 has side and end walls rising therefrom to form an enclosed chamber open at its upper end, and the side walls have elongated horizontal openings 5 formed and centrally disposed therein. Said side walls are shown as having a portion formed with extra thickness surrounding these openings to form a strengthening rib therefor. The side walls

are also shown as having spaced openings 6 formed therethrough. It will be noted that the side walls of the frame member are of greater height than the end walls and the same are suitably curved at their ends to converge with the end walls and present a pleasing appearance.

The base plate 1 of the frame is adapted to support a bearing or wearing plate 7, which plate has its position initially determined by a series of lugs 8 projecting inwardly from the walls of the frame member. The plate 7 is provided with a plurality of countersunk holes which are arranged to align with bolt holes formed through the lugs 4 which holes are adapted to receive suitable bolts or screws to securing the bearing in place. Below the openings 5, the side walls are provided with elongated projecting portions, the upper portions of which are formed as rack teeth 9. The end walls of the frame member are also thickened some distance below their upper ends to form projections extending toward the interior of the frame member.

The frame member is adapted to receive a pair of bearing rollers 10 which are suitably cored to relieve them of excessive weight, and also provided with central bores 11. Elongated plates 12 having rounded ends extend along the end portions of the roller members 10 at each end thereof and are provided with cylindrical projections 13 suitably spaced and which are arranged to enter the bored portions 11 of the bearing rollers. The plates 12 are also centrally bored intermediate of the projections 13 and a pin or bolt 14 passes through the openings 5 in the side wall and through this central bore of the plates. The plates are thus held in position in the frame member between the ends of the rollers and the side walls of the frame member. The pin 14 projects at each side of the side walls and counterweight members 15 are mounted thereon at either side of the frame member. The member 14 has a head on one end thereof and is suitably threaded at its other end to receive a flange nut or other retaining member 16 to retain the members 15 in proper position. As shown in Fig. 3, the members 15 are bored at their upper ends to loosely engage the pin 14 and have an enlarged counterweight portion at their lower ends, which is offset laterally from the upper portion to clear the rack 110.

portions 9 on the sides of the frame member. The members 15 have the portions thereof below the pin 14 and adjacent the frame member, formed as a gear segment having the 5 radial teeth 17 formed thereon, which teeth are adapted to engage with the teeth 9 of the rack formed on the frame member.

In operation, the bearing will normally occupy the position shown in Fig. 1. When 10 relative movement occurs between the bearing surfaces on the bolsters which engage the bearing rollers 10, the rollers will be moved and will traverse in one direction or the other on the bearing plates. This movement 15 will be transmitted to the plates 12; and by them, to the upper part of the counterweight members 15. Owing to the engagement of the teeth on these members with the rack on the frame member, said members 20 cannot move bodily longitudinally, but will be turned angularly about the pin 14 and the counterweight portion thereof elevated. Such elevation position of the counterweight is illustrated in Fig. 4 where the rollers are 25 shown at approximately the limit of their movement. The members 15 will tend to swing downwardly by gravity, and as the surfaces engaging the bearing rollers 10 resume their normal position, the counter- 30 weight members will assist the rollers 10 in returning to their central and normal position.

It will thus be seen that applicant has produced a simple and efficient roller side 35 bearing. The parts of the bearing can all be readily made as steel castings or forgings and the construction is such that the parts will require very little machining. It will, of course, be understood that various 40 changes may be made in the form, size and details of applicant's device without departing from the scope of the invention, which, generally expressed, consists in the matter shown and described and set forth 45 in the appended claims.

What is claimed is:

1. A side bearing for railway cars having in combination a frame member comprising a housing, a pair of bearing rollers disposed in said housing, connecting means for said rollers holding them in spaced relation, oscillating counterweights carried at the outer side of said housing, means engaging said connecting means and said counterweights, and means on said housing engaging said counterweights whereby said counterweights will be swung and moved out of normal position when said bearing rollers are moved.

60 2. A side bearing for railway cars having in combination a frame member comprising a housing, a plurality of bearing rollers disposed in said housing, counterweights mounted without said housing, and means 65 including a rack on said housing for mov-

ing said counterweights out of normal position when said rollers are moved from normal position.

3. A side bearing for railway cars having in combination a frame member comprising 70 a housing, a plurality of rollers disposed in said housing having central openings therethrough, a connecting member to said rollers having means engaging said central opening to hold the rollers in spaced 75 relation, a pin passing centrally through said connecting members and between said rollers and projecting on either side of said housing, depending counterweight members loosely mounted on said pin at each side of 80 said housing, and means on said housing engaging said counterweight member whereby the same will be swung on said pin when the bearing rollers are moved out of normal 85 position.

4. A side bearing for railway cars comprising a frame member, a bearing plate carried thereby, a pair of rollers supported on said plate having central openings there- 90 through, an elongated bar at each end of 95 said rollers having spaced projections thereon engaging in the central openings of said rollers to space the same counterweight means, and means connecting the same to said bar.

5. A side bearing for railway cars having in combination a frame member, counter- 100 weight members suitably supported at each side of said frame member, each having a gear segment formed thereon, a horizontal 105 rack at each side of said frame member with which the teeth of said segment engage, a plurality of bearing rollers disposed in said frame member, and means connecting the same to said counterweight member, where- 110 by said members will be moved out of normal position upon movement of said bearing rollers from normal position.

6. A side bearing for railway cars having in combination a frame member comprising 110 a housing having side portions, a plu- 115 rality of bearing rollers disposed in said housing, a pin passing transversely through the sides of said housing between said rollers, counterweight members swingingly 120 mounted upon said pin at each side of said housing and being formed with a gear seg- 125 ment adjacent said housing below said pin, a rack member formed at each side of said housing with which said segments engage, and means for transmitting the movement of the rollers to said pin, whereby the counter- 130 weight members will be swung thereon when the rollers move out of normal position.

7. A side bearing for railway cars having 125 in combination a housing, a plurality of bearing rollers supported therein, counter- 130 weight members supported to be bodily moved and also swung about their supports, and means for bodily moving and swinging

said counterweights upon movement of said bearing rollers.

8. The structure set forth in claim 8, said last named means including engaging means on said housing and counterweights.

9. A side bearing for railway cars comprising a housing, a plurality of bearing rollers supported for movement therein, means connecting said rollers and a counterweight

mounted for bodily and swinging movements upon movement of said rollers to return said rollers to their normal position.

In testimony whereof I affix my signature in presence of two witnesses.

FRANKLIN L. BARBER.
